By his Attorney *Joe Munk*

UNITED STATES PATENT OFFICE.

FRANK H. ROBINSON, OF BAYONNE, NEW JERSEY, ASSIGNOR TO NATIONAL METAL SPINNING & STAMPING CO., OF NEW YORK, N. Y., A CORPORATION OF NEW YORK.

LIGHTING FIXTURE.

Application filed October 31, 1922. Serial No. 598,075.

To all whom it may concern:

Be it known that I, FRANK H. ROBINSON, a citizen of the United States, residing at Bayonne, in the county of Hudson and 5 the State of New Jersey, have invented certain new and useful Improvements in Lighting Fixtures, of which the following is a specification.

My invention relates generally to improvements in electric lighting fixtures and 10 has specific reference to the construction of the supporting loop and the particular arrangement of the circuit wires leading through the same to the interior of the lighting fixture.

Electric lighting fixtures of the type which use a supporting loop of the character hereinafter described, are referred to generally as hanging fixtures and consist of a 15 ceiling plate or canopy and stem from which is suspended one end of a section of chain links attached at its opposite end to a supporting loop. The loop as a rule is a member having an eye to receive the end link 20 of the supporting chain and an annular base at its opposite end from which the main light supporting fixture or body is supported. The base is provided with a central bore which leads to a threaded opening, the 25 latter being adapted to receive one end of a pipe having a hicky secured to its lower end. The hicky in such a fixture supports the spindle which extends axially through the lower interior of the lighting fixture 30 and which receives a nut at this lower end adjustable against the under surface of a portion of the fixture to hold the latter in position. In order to wire such an arrangement it is necessary to thread the wire 35 through the central bore and into the end of the pipe, and thereafter through the pipe and out through the openings in the hicky. But one of the main difficulties encountered 40 has resulted from these threading steps which have a tendency to strip the insulation from the wire in at least four places during the operation, first where the wire enters the opening in the base of the loop and then again at the entrance to the pipe; third, at 45 the opposite end of the pipe and finally as the wire is drawn through the hicky. It has been found that a large percentage of 50 the fires started through faulty wires come

from a short circuit caused in the section of a wire which has been drawn through just 55 such an arrangement of sharp edges as described above. One of the principal objects of the present invention is to eliminate the central opening in the loop and do away 60 with both the pipe and hicky and in lieu 65 thereof to provide the base with separate or spaced slots or channels in its surface, the passages thus made communicating with the interior of the main light supporting fixture through an opening in the latter, 70 the opening being formed by rolling the edges of the material back upon itself to provide a smooth edge; whereby the single 75 strands of insulated wire leading from the canopy may be threaded through the separate openings or passages and against the rolled edge of the opening in the fixture without fear of in any way impairing the insulation about the wires.

A further object of the invention is to 80 provide the base of the loop member with a depending threaded stem which is adapted to project through the main fixture to support the latter in the manner hereinafter set forth.

The invention is illustrated in the accompanying drawing, in which, Figure 1 is an elevational view of a hanging type of lighting fixture equipped with my improved supporting loop; Figure 2 is a perspective view 85 of the supporting loop; and Figure 3 is a bottom plan view of the loop.

In the drawing, reference being had particularly to Figure 1, 10 designates a ceiling plate or canopy and 11 a depending section 90 of chain engaged at its lower end in a supporting loop 12. The loop 12 connects with the upper portion of the main light supporting fixture 13 and is provided with a threaded stem 14 projecting axially thereof and 95 through the fixture to receive a nut 15 at the outside of the lower end of the fixture 13. The latter is further provided with side arms 16 from which the usual light shades 17 are suspended. The lower end of the 100 canopy 10, in the present fixture, is provided with a hollow stem 18 and drilled cap 19 through which circuit wires or ends 20 lead from the ordinary outlet box, not shown, to the lower portion of the fixture. It 105 is customary to use a covering for such wires

as will match in color the metallic finish of the links in the chain 11, and with the wires so colored they are practically invisible and may be interwoven with the links of the chain without materially changing the appearance of the chain itself.

Referring now to the supporting loop 12, and especially to Figures 2 and 3, the loop proper comprises a metal member having 10 a longitudinally disposed loop portion 21 provided at its lower end with an integral annular flange 22, the latter being formed with a projecting under ring or step 23, which is of a smaller diameter than the 15 flange 22. The ring or step 23 together with flange 22 may be drilled and tapped to receive one end of the threaded stem 14, but the opening for the stem will not project entirely through this portion of the loop. 20 In order that the loop 12 may be firmly attached to the main supporting fixture 13 the wall of the central axial opening 24 therein is of a size to embrace the ring portion 23 of the flange 22, as clearly shown 25 in Figure 2. In order to insure against possible injury of the wire when brought into contact with the adjacent edge of the opening 24, the edges of the latter are formed by bending or rolling the material back upon 30 itself to provide a smooth wall, as shown in Figure 2. The wires 20, as previously stated, follow the links 11 and then drop over the loop portion 21 and enter the fixture 13 through a pair of oppositely disposed 35 slots or channels 25 which are cut or cast into the surface of the flange 22 and ring 23. Both channels 25, when the loop is assembled with the fixture 13, form one wall of the inlet openings into the interior of the 40 fixture, while the smooth adjacent periphery of the opening 24 provides the opposite walls. In this manner two distinct openings are provided, one for each cord or wire 20, which may be readily and safely inserted 45 through the openings thus made without fear of injury to the insulation on the wire.

What I claim is:—

1. A supporting loop for lighting fixtures, comprising a loop portion and an integral annular end member, said end member being 50 provided with a stepped bottom surface to project into said lighting fixtures and longitudinally disposed open channels on opposite sides thereof, said channels being of a depth projecting beyond the stepped 55 surface, whereby direct communication is established between the outside of the annular member and the interior of the fixture.

2. In a lighting fixture, the combination with a light supporting body provided with 60 central openings at opposite ends, of a supporting loop therefor, comprising a loop portion and an integral annular end portion provided with a stepped under surface adapted to project into the opening in one 65 end of the body, the annular end portion being provided with open longitudinal channels at opposite sides communicating with the interior of the body through the said openings, a threaded stem screwed in 70 a threaded bore extending to a point short of the opening forming the said loop, said stem projecting axially of the said supporting loop and through the opening at the opposite end of the body, and a nut for said 75 stem adjustable against the said body.

3. In a fixture of the character described an integral supporting loop having a base portion provided with exteriorly and oppositely disposed open wire channels the combination of a light supporting fixture having a 80 central opening to receive the base portion of the said loop, the edges of the said opening being formed by bending or rolling the material back upon itself to provide a 85 smooth surface exposed to the opposite face of the channels in the base, substantially as described.

In testimony whereof I affix my signature.

FRANK H. ROBINSON.
